UNITED STATES PATENT OFFICE.

FRANK L. COOLEY, OF BROOKLYN, NEW YORK.

REFILLABLE CARTRIDGE-FUSE.

1,354,284.

Specification of Letters Patent. Patented Sept. 28, 1920.

Original application filed January 8, 1919, Serial No. 270,113. Divided and this application filed September 11, 1919. Serial No. 323,102.

To all whom it may concern:

Be it known that I, FRANK L. COOLEY, a citizen of the United States, residing at Brooklyn, in the county of Kings and State 5 of New York, have invented certain new and useful Improvements in Refillable Cartridge-Fuses; and I do hereby declare the following to be a full, clear, and exact description of the invention, such as will enable others skilled in the art to which it 10 appertains to make and use the same, reference being had to the accompanying drawings, and to characters of reference marked thereon, which form a part of this specification.

15 The present invention has reference, generally, to improvements in cartridge fuses; and the invention relates, more particularly, to a novel construction of refillable cartridge fuse of the type disclosed in my prior 20 application for Letters-Patent bearing Serial No. 270,113, filed January 8, 1919, and of which the present application is a division.

25 The present invention has for its principal object to provide a novel construction of refillable cartridge fuse having novel removable end ferrules combined with knife blade contact members arranged with means for securing the end ferrules in closing and 30 sealing relation to the chamber of the containing cartridge and the knife blade contacts in desired electrical engagement with the inclosed fuse element.

Other objects of the present invention, 35 not at this time more particularly enumerated, will be clearly understood from the following detailed description of the same.

With the various objects of the present invention in view, the same consists, primarily, in the novel construction of refillable 40 cartridge fuse hereinafter set forth, and the invention consists, furthermore, in the novel arrangements and combinations of the various devices and parts, as well as in the details of the construction of the same, all of 45 which will be hereinafter more fully described, and then finally embodied in the claims appended to this specification.

The invention is clearly illustrated in the 50 accompanying drawings, in which:—

Figure 1 is a top or plan view of the novel construction of refillable cartridge fuse made according to and embodying the principles of my present invention; Fig. 2 55 is a side elevation of the same, Fig. 3 is an

end view of the same; Fig. 4 is a longitudinal vertical section of the same taken on line 4—4 in said Fig. 2, said view being drawn on an enlarged scale; Fig. 5 is another detail longitudinal vertical section of 60 one end of the same, taken on line 5—5 in said Fig. 4; Fig. 6 is an end view of the cartridge fuse, with the ferrule and knife contact removed therefrom; and Fig. 7 is a detail side elevation of one end of the cartridge casing showing the ferrule thereon broken away to disclose the mortised seat provided for the cross-nut of the ferrule and knife blade contact fastening devices.

Similar characters of reference are employed in all of the hereinabove described views, to indicate corresponding parts.

Referring now to said drawings, the reference character 1 indicates a tubular casing, made of some suitable insulating or non-conducting material, which provides an interior fuse chamber 2.

Provided in the walls at each end of said casing 1 are a pair of transversely opposite mortised seats 3, the sides 4 of which incline inwardly toward the outer end of the casing. Dovetailed into said respective mortised seats 3 are the ends of a transversely disposed cross nut or anchor bridge 5, which is shaped in cross-section to correspond to 85 the shape of said mortised seats, and which is held, by engagement in said seats, against outward displacement or withdrawal from the open ends of the said casing 1.

The reference-character 6 indicates a removable fuse link having perforations 7 for determining the width of blowing portions thereof, and provided with end terminals 8. Said fuse link, when properly assembled, passes longitudinally and diagonally 90 through the fuse chamber 2, with its end terminals 8 extending over the cross nuts or anchor bridges 5, one terminal passing over the upper side of one cross nut or anchor bridge, and the opposite terminal passing under the lower side of the opposite cross nut or anchor bridge, thus assuring 95 the diagonal disposition of the main body of the fuse link within the fuse chamber, so that the intermediate blowing portion thereof is assured of being centered in position intermediate of the inner sides of the walls of said casing 1.

The reference character 9 indicates the end ferrules, the annular skirts 10 of which 110

are telescopically engaged over the ends of the casing 1. Said ferrules 9 are adapted to close the ends of the casing 1. Said ferrules 9 are constructed in a novel manner for the 5 purpose of so engaging the open ends of the casing 1 as to securely seal the latter against the escape of flame therefrom when the fuse link blows. To this end each ferrule is provided in its end wall with an inwardly de- 10 pressed and tapered concentric boss 11, the periphery 12 of which is carried into engagement with the marginal edge 13 of the opening of the casing ends in a sealing relation thereto in much the same way as a cork or 15 stopper is engaged in the neck of a bottle. The transverse wall of each ferrule boss 11 is provided with a slot opening 14 upon either side of which are provided fastening screw openings 15. The cross nuts or anchor 20 bridges 5 are provided with a pair of spaced internally threaded openings 16, one on either side of the position of the fuse link terminals 8, and with which the screw openings 15 of the ferrules are alined, when the 25 latter are engaged over the casing ends.

The reference-character 17 indicates a metallic knife-blade contact element having at its inner end laterally and oppositely projecting foot pieces 18 provided with perforations 30 adapted to be alined with the openings 15 of the ferrules and openings 16 of said cross nuts or anchor bridges 5 so that fastening screws may be passed through all the openings thus alined. Before assembling 35 the ferrules the free ends of the knife-blade contact elements 17 are respectively passed outwardly through the slot opening 14 until the foot pieces 18 are engaged against the inner sides of the transverse walls of the fer- 40 rule bosses 11. The ferrules are then slipped over the ends of the casing until the exposed surfaces of the foot pieces 18 are electrically engaged against the end terminals 8 of the fuse link. Fastening screws 19 are 45 then passed through the ferrules and foot pieces 18 to screw into the threaded receiving openings 16 of the cross nuts or anchor bridges 5, whereby the ferrules bind said foot pieces against the end terminals 8 of the 50 fuse link, and at the same time forcing the periphery 12 of the ferrule bosses 11 into sealing relation to the open ends of the casing 1, the outer surface of said cross nuts or anchor bridges 5 being depressed as at 20 55 to assure an unobstructed close fit thereof in the said ends. It will be noticed from the above description that the knife blade contact elements are detachable from the ferrules, by withdrawing the blade thereof 60 through the slot openings 14. This construction is of marked advantage since it enables the removal of said contact elements, so that any corrosion or other desecration of the bottom of the foot pieces 18 may be removed 65 by emery cloth or the like, whereby the con-

tacting surfaces thereof, adapted to electrically engage the fuse link terminals 8, may be thoroughly cleaned and brightened in a manner adapted to insure a perfect electrical contact with the end terminals of said 70 fuse link when the parts are reassembled.

I am aware that some changes may be made in the several arrangements and combinations of the various devices and parts, as well as in the details of the construction 75 of the same, without departing from the scope of my present invention as set forth in the foregoing specification, and as defined in the appended claims. Hence, I do not limit my invention to the exact arrangements and combinations of the several devices and parts as described in said specification, nor do I confine myself to the exact details of the construction of the said parts as illustrated in the accompanying drawings. 80

I claim:—

1. A refillable cartridge fuse comprising a tubular casing, transverse cross nuts fixed within the open ends of said casing, a fuse link having end terminals engaged over said 90 cross nuts, removable ferrules slidable over the ends of said casing, said ferrules having diametrically disposed slots in their end walls, detachable knife-blade contact elements having oppositely and laterally directed foot-pieces at their inner ends, said knife-blade contact elements being adapted to be passed outwardly through said slots, and fastening means adapted to pass through said end walls of said ferrules and 100 through said foot-pieces of said knife-blade contact elements to engage said cross nuts to clamp said foot-pieces in electrical contact with the end terminals of said fuse link. 95

2. A refillable cartridge fuse comprising 105 a tubular casing, transverse cross nuts fixed within the open ends of said casing, a fuse link having end terminals engaged over said cross nuts, removable ferrules slidable over the ends of said casing, the end walls of said 110 ferrules having inwardly depressed bosses the peripheries of which are adapted to be pressed into sealing relation to the open ends of said casing, the transverse walls of said bosses having diametrically disposed slots 115 therein, detachable knife-blade contact elements having oppositely and laterally directed foot-pieces at their inner ends, said elements being adapted to be passed outwardly through said slots, and fastening 120 screws adapted to be passed through said transverse walls and through said foot-pieces to screw into said cross nuts whereby said bosses are drawn to said sealing relation to the ends of said casing, and said 125 transverse walls of said bosses depressed to force said foot pieces into electrical contact with said fuse link end terminals.

3. A refillable cartridge fuse comprising a tubular casing, transverse cross nuts hav- 130

ing their ends mortised into the walls of said casing at the extremities of the latter to hold the same against outward withdrawal from said casing extremities, a fuse 5 link having end terminals engaged over said cross nuts to stretch said link longitudinally and diagonally through the interior of said casing, removable ferrules slideable over the ends of said casing, said ferrules having diametrically disposed slots in their end walls, detachable knife blade contact elements having oppositely and laterally directed foot pieces at their inner ends, said knife blade contact elements being 10 adapted to be passed outwardly through said slots; and fastening means adapted to pass through said end walls of said ferrules and through said foot pieces to engage said cross nuts to clamp said foot pieces in 15 electrical contact with said end terminals of said link.

4. A refillable cartridge fuse comprising a tubular casing, transverse cross nuts having their ends mortised into the walls of said casing at the extremities of the latter to hold the same against outward withdrawal from said casing extremities, a fuse 25 link having end terminals engaged over said cross nuts to stretch said link longitudinally

and diagonally through the interior of said 30 casing, removable ferrules slideable over the ends of said casing, the end walls of said ferrules having inwardly depressed bosses the peripheries of which are adapted to be pressed into sealing relation to the open ends 35 of said casing, the transverse walls of said bosses having diametrically disposed slots therein, detachable knife blade contact elements having oppositely and laterally directed foot pieces at their inner ends, said 40 elements being adapted to be passed outwardly through said slots, and fastening screws adapted to be passed through said transverse walls and through said foot pieces to screw into said cross nuts on either 45 side of said link terminals whereby said bosses are drawn to said sealing relation to the ends of said casing, and said transverse walls of said bosses depressed to force 50 said foot pieces into electrical contact with said link terminals.

In testimony, that I claim the invention set forth above I have hereunto set my hand this 3rd day of September, 1919.

FRANK L. COOLEY.
